DESIGN FOR A COMMEMORATIVE EMBLEM OR SIMILAR ARTICLE

Milton D. Cavagnaro, San Francisco, Calif., assignor to San Francisco Bay Exposition, San Francisco, Calif., a corporation of California

Application March 19, 1940, Serial No. 91,078

Term of patent 3½ years

To all whom it may concern:

Be it known that I, Milton D. Cavagnaro, a citizen of the United States and residing at the city and county of San Francisco and State of California, have invented a new, original, and ornamental Design for a Commemorative Emblem or Similar Article, of which the following is a specification, reference being had to the accompanying drawing, forming a part thereof.

The figure is a face view of a commemorative emblem or similar article showing my new design.

The design has no substantial thickness.

I claim:

The ornamental design for a commemorative emblem or similar article, substantially as shown and described.

MILTON D. CAVAGNARO.
